PACKAGING CUP FOR FOOD PRODUCTS OR THE LIKE

Howard H. Kulow, Berea, Ohio, assignor to Wilson
Plastics, Inc., Sandusky, Ohio, a corporation of Ohio

Filed Mar. 26, 1962, Ser. No. 69,413

Term of patent 14 years

(Cl. D58—17)

Fig. 1

FIGURE 1 is a front perspective view of a packaging cup for food products or the like, embodying my new design; and

FIG. 2 is an enlarged fragmentary sectional view there-of taken on the line 2—2 of FIG. 1.

The side not shown is substantially the same in appearance as the side shown.

I claim:

The ornamental design for a packaging cup for food products or the like, substantially as shown.
